UNITED STATES PATENT OFFICE.

CARRICK PAUL, OF HURSTVILLE, NEW SOUTH WALES, ASSIGNOR TO THE PACIFIC PEARL FISHING COMPANY, LIMITED, OF SYDNEY, NEW SOUTH WALES.

SUBMARINE VESSEL OR DIVING APPARATUS.

SPECIFICATION forming part of Letters Patent No. 622,529, dated April 4, 1899.

Application filed May 2, 1898. Serial No. 679,531. (No model.)

To all whom it may concern:

Be it known that I, CARRICK PAUL, civil engineer, a subject of the Queen of Great Britain, residing at Carrington avenue, Hurstville, near Sydney, in the British Colony of New South Wales, have invented new and useful Improvements in Submarine Vessels or Diving Apparatus, of which the following is a specification.

10 This invention relates to submarine vessels or diving apparatus specially devised for working under water in comparatively great depths, and so as to be practically safe and easy in operation.

15 The submarine vessel or diving apparatus to which the present improvements refer is of the kind in which the operators are "housed" in a shell or inclosure which is in communication with the atmosphere above the level 20 of the water; and the present improvements have been specially contrived to enable the operators to have better control than heretofore over the lowering and raising of the vessel and its movement generally and to provide 25 the operators with more effective and more easily manageable tools or grips than heretofore.

According to this invention, besides the main vessel or shell or inclosure for the operators, there is a second but smaller vessel, hereinafter referred to as the "auxiliary" vessel, which can be extended outwardly of the main vessel and withdrawn inwardly into the main vessel in order to increase the displacement 30 of the whole, so that the vessel will rise, or to lessen the displacement, so that the vessel will sink. The joints between the auxiliary and main vessels are practically air-tight and waterproof, while the inner end of said auxiliary vessel is open to the main vessel and draws its supply of air therefrom. In combination with the main vessel there is arranged a sliding dead-weight, so that the center of gravity of the apparatus may be altered 35 at will to suit its level or its inclination to the operation performed. At the opposite end of that from which the auxiliary vessel protrudes, hereinafter referred to as the "front" or "forward" end, is the gear for lifting and 40 gripping, such being of peculiar construction,

as hereinafter particularly described, and at this forward end also are windlasses outside of the vessel capable of being revolved from within, so that the vessel may be easily maneuvered by means of warps from moorings or 55 the like. In combination with the main vessel there is a dome or entrance extension on which is tightly fixed a door or cover adapted to be released from the inside and from the outside, and in combination with the vessel 60 is a safety connection for the air supply and escape pipes, which is self-closing under stress of outside pressure.

In order that this invention may be clearly understood, reference is now made to the drawings herewith, in which—

Figure 1 is a longitudinal sectional elevation of a submarine vessel or diving apparatus constructed according to these present improvements. Fig. 2 is an elevation of the 7c front end. Fig. 3 is a cross-section on the line *a a* of Fig. 1, and Fig. 4 is a view of the end hereinafter referred to as the "back" end. Figs. 5 and 5^a are enlarged side views of the gripper-arms, and Figs. 6 and 6^a are plans of 75 the same. Fig. 7 is a part-sectional elevation of the gripper-jaws. Fig. 8 is a part-sectional plan of the same. Fig. 9 is a transverse section of the same on the line *b b* of Fig. 7. Figs. 10 and 11 are respectively an 80 elevation, partly in section, and an inverted plan of safety-valve connections between the vessel and the air supply and escape pipes.

A is the main vessel, preferably cylindrical in form, having at the front end thereof dome 85 or entrance-way B. On top of this dome B is a water-tight door or cover B', sitting upon ring B², hinged at B³ and pressed air-tightly upon top flange of dome B by screw B⁴. Internally of it and taking under the ring B² is 90 a dog B⁵, by means of which and ring-screw B⁶ the cover B' is caused to make an air-tight joint on ring B². If at any time it is necessary for the operators to make an exit from the vessel A without assistance from outside, by 95 unscrewing screw-bolt B⁶ the dog B⁵ is loosened and the cover B' pushed outwardly and away from the ring B² to provide a way for such exit.

Extending from the back end of the vessel 100

- A inwardly to a ring-support C' is an annular channel or chamber C³, blocked at the inner end and formed of shell C³ and inner shell C⁴, said inner shell C⁴ being blocked at its outer end. In this annular channel, between shells C³ and C⁴, takes the inner end of a dome-shaped cylinder or casing forming the auxiliary vessel C, which is adapted to travel longitudinally in said channel, so that it may be extended outwardly of the main vessel A and be withdrawn from any extended position. Joining the shell C³ with the back end of the vessel A is an annular bracket (or rather stuffing-box) C⁵ for the reception of a gland C⁶ around the vessel C, so as to make a watertight joint between the back end of vessel A and said secondary vessel C. The gland C⁶ is tightened in the stuffing-box C⁵ by means of a series of studs and nuts, one of which is shown and marked C⁷. The auxiliary vessel C is extended and drawn in by means of an internally-threaded ram or pole D, extending from the dome end through the back or blocked end of shell C⁴ to close up to the end inner end of said shell C⁴. On this end of the shell C⁴ is a central bearing D², supporting the inner end of the screw-ram D', which for the purpose of passing therethrough a shaft or spindle to carry a screw-propeller is made hollow. On the back or blocked end of auxiliary vessel C⁴ is a stuffing-box C⁸, in which takes gland C⁹ for making a tight joint around the ram or pole D. This gland C⁹ is tightened from the inner end of the shell C⁴ by means of nuts C¹⁰ on long studs C¹¹, on which are the sleeves or tubes C¹², so that when the nuts C¹⁰ are tightened such sleeves or tubes will force said gland C⁹ into said stuffing-box C⁸. The sleeves and studs are supported by and form guides for the inner end of the ram or pole D by reason of passing through star bracket or flange C¹³. It will be seen from the above that no matter how the auxiliary vessel C may be moved longitudinally outwardly or inwardly by means of the ram or pole D and screw-ram D' impassable joints are maintained between the outer water and the interior of the vessel. The screw-ram D' carries on its inner end a worm-wheel D³, in which gears the worm or endless screw D⁴ in bearings on brackets D⁵. On the end of the spindle of said worm or endless screw D⁴ is a pulley D⁶, around which and around a hand-wheel D⁷ in a convenient situation in the vessel A is an endless chain or belt, so that by revolving said hand-wheel D⁷ the screw-ram D' is revolved within the female thread of the ram or pole D to longitudinally move the vessel C as may be desired. At a convenient part on the top of vessel A is fixed the safety connection of the air-supply pipe E, (from the surface,) which pipe E is inside of the air-escape pipe E^X, which branches to self-closing ball-valve E' at back of cock or valve E². The supply-pipe bends to self-closing ball-valve E³ and in front of cock or valve E⁴. Upon any inrush of water,

&c., owing to accident, the balls close their respective valves E' and E³, and thus give the operators in the vessel opportunity to close the cocks or valves E² and E⁴ and prevent flooding, &c., of the vessel.

In the vessel A is a weight F, sliding on a rod F', which is held at each end by brackets or pillars, as shown. This weight F can be easily shifted longitudinally by hand, as may be desired, to balance any extension or withdrawal of the auxiliary vessel C to balance the vessel A and its extension C and to alter the level or inclination of the whole vessel, as may be desired or required.

Where necessary, the vessel A, particularly at the front end and in any convenient situation, has ports or light-holes, (marked J,) and such ports or light-holes can be placed where convenient in the sides—say as shown at J'. If necessary or desirable, a screw-propeller may be placed at the back end of the vessel—that is, at the back end of the auxiliary vessel C—in which case a shaft, as shown by dotted lines, is passed through the hollow screw-ram D' and through a stuffing-box at the outer end of the ram or pole D, as shown by dotted lines. This shaft of the screw-propeller may be revolved or operated in a similar manner to that which has been described in reference to the screw-ram D'.

The lifting and operating appliances comprise a special arrangement of lazy-tongs extension-pieces, on the outer end of which, operated by a handle inside the vessel, are jaws or grippers also operated internally of the vessel, though by independent devices. On the front end of the vessel A is the socket part L^X of a ball-and-socket joint, the ball part L' being upon a pipe L, on the end of which is a stuffing-box and gland L², and through which passes rod M. On the outer end of this pipe L is carried a bracket or L-piece M', fitted thereto by means of the collars M² and M³. The rod M is screwed at the end after passing through the bracket M' and collar M⁴, and it passes through a nut M⁵, pivoted to the first joint of the lazy-tongs extension. From the bracket M' short links N' are connected to the inner end of the lazy-tongs extension N. This lazy-tongs extension N is constructed generally as shown in the drawings, and it terminates after as many cross-joints as may be convenient at a point at which is attached the back end O' of the bottom grip O, which is bent downwardly, as shown. Just inwardly of this connection are pivoted short links N², carrying a pivoted guide N³ over the tail O² of the back end O' of the gripper O. To the bent back end O' of the bottom gripper O is affixed the box-piece P, carrying the pivot-bolt Q' of the upper jaw or gripper Q, and also covering the devices by which this upper jaw Q is opened from or closed upon the lower gripper O. To this box-piece P is also affixed the inner end of spring R, adapted to press the upper jaw Q toward or onto lower gripper O. Attached

- to the inside of box-piece P is a bearing S² for the spindle S', on which is cam S. The inner end of said spindle S' after passing through the back end O' of the bottom grip- 5 per O has a union S³, to which is attached the outer end of a flexible shaft T. The upper gripper Q extends backwardly of its pivot Q' and terminates in a tailpiece Q². Upon revolution of flexible shaft T the cam S presses upon and revolves upon the tail Q² and so elevates the front or outer end of the gripper Q, opening the pair of grippers, which being placed on the article or other thing to be lifted or operated upon and the flexible shaft 10 T being further operated the spring R will press the gripper Q toward the gripper O and cause said grippers to grip said article between them. The edge of the upper gripper Q is preferably serrated, as shown, and both the grip Q and the grip O are perforated or have orifices of various forms, as shown. The flexible shaft T extends backwardly from the front end of the lazy-tongs extension to a union on the spindle T', which passes through 15 stuffing-box and gland T² and terminates in handle T³. The operating of said handle T³ by the persons in the vessel A will open and close the grippers or grips as said persons may desire. The windlass-barrels U are carried in 20 bearings U' on brackets U², and have upon their ends beveled tooth-wheels U³, in each of which gears the respective beveled pinion V' on the end of spindle V, passing through gland and stuffing-box V² and terminating in hand-wheel V³. The revolution of said hand-wheel V³ by the operators will revolve its particular windlass-barrel and so wind or unwind the warp from mooring-anchors or the like to shift the position of the submarine vessel. 25 Having now particularly described and ascertained the nature of my said invention and in what manner the same is to be performed, I declare that what I claim is—
1. In a submarine vessel or diving apparatus, the combination with a main vessel A provided with inner concentric shells C³, C⁴, stuffing-box C⁵ and gland C⁶, of an auxiliary vessel C adapted to slide between said shells, and mechanism for protruding and retracting 30 said auxiliary vessel to vary the displacement of the whole apparatus, substantially as described.
  2. In a submarine vessel or diving apparatus, the combination with a main vessel A, inner concentric shells C³, C⁴, stuffing-box C⁵, gland C⁶, and auxiliary vessel C adapted to slide between said shells, of a tubular ram or pole D attached to the closed end of said auxiliary vessel, stuffing-box C⁸, gland C⁹, screw- 35
- ram D' geared with the interior of the tubular ram D, and means for revolving said screw-ram D', substantially as described. 60
3. In a submarine vessel or diving apparatus, the combination with a main vessel A, and an auxiliary vessel C adjustably supported in said main vessel and having fluid-tight connection therewith, of a tubular ram or pole attached to the closed end of the said auxiliary vessel, a screw-ram D' geared with the interior of said tubular ram, and gearing 65 for revolving said screw-ram, to protrude or retract the auxiliary vessel, substantially as described. 70
  4. In a submarine vessel or diving apparatus, the combination with the entrance-dome B, of a ring B² hinged to the top of said dome at one side, a cover B' seated upon said ring, a dog B⁵ adapted to engage the under side of said ring within the dome, a screw-bolt B⁶ accessible from the inside of the dome and 75 connecting said cover and dog, whereby the cover and the ring and the dog are movable together on the hinge B³ of said ring, a screw B⁴ located on the outside of the dome opposite said hinge, and a nut to clamp the said cover 80 and ring onto said bolt and accessible from the outside of the dome, substantially as described. 85
  5. In a submarine vessel or diving apparatus, the combination with a ball-jointed tube 90 L, and lazy-tongs N carrying grippers at one end, of a screw-rod M, extended through said tube and connected with the lazy-tongs to actuate the same, substantially as described.
  6. In a submarine vessel or diving apparatus, the combination with the lazy-tongs N, of a bottom-gripper O and spring-gripper Q, and mechanism adapted to be actuated from within the said vessel to open the spring-gripper away from the bottom-gripper, sub- 95 stantially as described. 100
  7. In a submarine vessel or diving apparatus, the combination with the gripper O and spring-gripper Q having tailpiece Q², of the cam S having connection to a flexible shaft 105 connected to operating mechanism in the interior of the vessel, substantially as described.
  8. In a submarine vessel or diving apparatus, the combination with the windlass-barrel U carried in bearings outside the vessel, of 110 spindles V connected with the shaft of said windlass by bevel-gearing, and stuffing-boxes for said spindles, substantially as described.

Dated this 22d day of March, 1898.

CARRICK PAUL.
